APPARATUS FOR SETTING HOLLOW RIVETS

Theodore A. Pepper, Middletown, Ohio

Application February 24, 1943, Serial No. 476,960

6 Claims. (Cl. 218—19)

This invention relates to a novel implement for spinning hollow rivets into place.

It is the object of the present invention to provide a simplified riveting procedure which enables the setting of hollow rivets into place quickly and expeditiously with uniformly good results.

It is a further object of the invention to provide a tool which is simple and rugged in design and which enables the setting of hollow rivets to be executed quickly and with certainty.

It is the object of the present invention to provide a simplified tool for setting hollow rivets, which are accessible from only one end of the rivets, by a metal spinning operation resulting in a distortion, expansion or upsetting of the free ends of the rivets within controllable limits.

The present invention proceeds upon the principle of spinning the free end of a hollow rivet to obtain an enlargement thereof and the utilization of centrifugal force to place the operative spinning member of a tool for this purpose into position for the execution of the metal spinning operation, which member normally occupies an inactive position to permit the tool carrying the member to be inserted freely through the center of the hollow rivet in the course of introducing and withdrawing the tool from the field of action of the spinning member on the rivet. Preferably, the enlargement of the clinching portion of the rivet to an extent greater than the diameter of the rivet holes of the parts to be joined is executed simultaneously with a pressing action between the ends of the rivet, the extent of which is controllable to a fine and accurate degree.

Other objects and purposes will appear from the more detailed description of the invention following hereinafter, taken in conjunction with the accompanying drawings, wherein

Fig. 1 is a side elevation of the apparatus preparatory to the execution of the riveting operation;

Fig. 2 is a left end view of the tool support shown in Fig. 1;

Fig. 3 is a top view of the tool support shown in Fig. 1;

Fig. 4 is an enlarged vertical sectional view with certain parts in elevation of the riveting tool in position preparatory to the execution of the riveting operation; and

Fig. 5 is a corresponding view of Fig. 4 showing the parts at the termination of the riveting operation.

The present invention is illustrated in Fig. 1 in its application to a portable riveting tool mak-

ing use of a conventional electric hand drill in which the tool in accordance with the present invention is substituted for the drill. In the drawings, the parts to be joined, A and B, of any desired materials, are provided with suitable rivet holes in which is disposed the hollow rivet R having a shank of a diameter slightly less than the diameters of the rivet holes in members A and B and a head H. The object of the invention is to upset the free end of the rivet R against the member B from the side of the rivet remote from the free end. Accordingly, the invention comprehends the use of a mandrel member T which may be inserted in the chuck 20 of the electric hand drill, or which may be operated by any other driving means to cause the same to rotate at a substantially high speed, preferably at least 1000 R. P. M.

A slot 10 is provided near the free end of the mandrel T in which is pivotally mounted member 11 by pivot pin 12. Member 11 may be formed of an alloy steel or any other sufficiently rugged material. A leaf spring 13 is shown anchored at one end in the tool with the free end thereof fitting in a groove in the rear face of member 11 to normally retain the member 11 within the confines of the slot, as shown in dotted lines in Fig. 4. In such position, the spinning member 11 presents no hindrance to the passage of the tool through the center of the hollow rivet and the members cooperating therewith. Following the insertion of the mandrel with the spinning member beyond the end of the hollow rivet R, the energization of the electric motor M rotates the mandrel at a high speed and the centrifugal force of the rotation upon the member 11 causes the same to be thrown out laterally from the tool against the force of the spring member 13 to bring member 11 into the position shown in full lines in Figs. 4 and 5, rocking around the pivot pin 12. Thereupon, the member 11 may coact with the free end of the hollow rivet R to spin the same beyond the diameter of the rivet holes in the plates to be joined, A and B, into a conformation corresponding to the outline of the member 11, as shown in Fig. 5. The cessation of the rotation of the tool, or a sufficient diminution of the speed thereof causes the return of the spinning member 11 into the confines of the slot 10 when the tool is retracted axially from the spinning position, whereupon the tool is capable of withdrawal from the hollow rivet which is now expanded or upset at the end opposite the head H. The tool may then be subsequently inserted into another rivet for a similar operation.

In order to make possible the spinning of the

free ends of the rivets with rapidity and dispatch and uniformly good results, pressure is brought to bear on the spinning member 11 simultaneously with the rotary movement thereof and the drawings illustrate one manner of performing the dual operation simultaneously.

A bracket 21, having semi-circular extensions at the upper end thereof fitting around the opposite sides of the end of the electric motor M is clamped to the latter by bolts and nuts 22 and 23. Arms 24 project from an intermediate portion of the bracket 21 to which is pivoted the midportion of a manually operable member 24 by means of pivot pin 30. One end of member 24 is formed as a bifurcated extension 26 on which is fitted a backing slide 27 having an aperture 28 therethrough, through which passes the tool T and supports the slide 27 thereby. The forward face of the backing slide has a concave recess therein 28 adapted for cooperation with the head H of the hollow rivet to thereby exert a suitable pressure on that end of the rivet. The opposite end of the member 24 is formed as a hand grip 25 which is adapted to be grasped by an operator together with the lower end of bracket 21. Normally the bracket 21 and the handle 25 are maintained in spaced position by the interposition of a coil spring 35 therebetween. Pressure of the member 25 towards the bracket 21 gives rise to a relative movement between the spinning member 11 and the backing slide 27 causing a pressure to be exerted against the opposite ends of the rivet to facilitate the expansion of the free end of the rivet in the course of the rotation of the spinning member 11. In order to control the amount of pressure exerted on the opposite ends of the rivets, a set screw 36 may be provided on the member 24 which serves to adjust the permissive movement between members 21 and 25 to determine the limit of movement of member 11 and the end of the rivet distorted thereby with respect to the opposite headed end H of the rivet. Thereby the riveting operation may be executed quickly and without guess work as regards the uniformity of the riveting action.

Other arrangements may be devised to obtain a pressing of the spinning member against the free end of the rivet during the spinning operation, and while I have described my invention as embodied in a specific form and as operating in a specific manner for purposes of illustration, it should be understood that I do not limit my invention thereto, since various modifications will suggest themselves to those skilled in the art without departing from the spirit of my invention, the scope of which is set forth in the annexed claims.

I claim:

1. A manually portable riveting tool comprising a rotary mandrel for insertion into one end of a hollow rivet disposed in rivet holes of parts to be joined and having a slot therein, a member pivoted to said mandrel and resiliently retained in said slot to permit the free passage through the rivet of the mandrel with the member therein, means for rapidly rotating said mandrel to throw out said member laterally of the mandrel about the pivot mounting thereof by the resulting centrifugal force, means to retract the mandrel during the rapid rotation thereof and means to retain said first-mentioned end of the hollow rivet against retraction.

2. A manually portable riveting tool comprising a rotary mandrel for insertion into the headed

end of a hollow rivet disposed in rivet holes of parts to be joined and having a slot therein, a member pivoted to said mandrel and resiliently retained in said slot to permit the free passage through the rivet of the mandrel with the member therein past the opposite end of the hollow rivet, means for rapidly rotating said mandrel to throw out said member laterally of the mandrel about the pivot mounting thereof by the resulting centrifugal force, means to retract the mandrel during the rapid rotation thereof and to retain said headed end of the hollow rivet against retraction to expand the opposite end of the hollow rivet beyond the diameter of the rivet holes.

3. A riveting tool comprising a rotary mandrel for insertion through the head end of a headed hollow rivet disposed in rivet holes of parts to be joined having a slot extending along one portion of the mandrel longitudinally thereof and a spinning member pivotally mounted therein, spring means abutting said member for resiliently retaining said member in said slot to permit the free passage of the mandrel with the member therein past the opposite end of the hollow rivet, means for rapidly rotating said mandrel to throw out said spinning member laterally of the tool by the resulting centrifugal force, and means to retract the mandrel during the rapid rotation thereof and to retain said head end of the hollow rivet against retraction.

4. The combination set forth in claim 3 wherein said last-mentioned means comprises a bracket mounted on the means for rotating the mandrel, and a manually operated member pivotally mounted on said bracket and carrying a seat for the head end of the rivet whereby relative movement between said bracket and member carries the spinning member towards said seat to press the opposite ends of the rivet towards each other.

5. The combination set forth in claim 3 wherein said last-mentioned means comprises a bracket mounted on the means for rotating the mandrel, and a manually operated member pivotally mounted at a midportion thereof on said bracket; one end of said last-mentioned member carrying an apertured seat fitting against the head of the rivet through which passes the rotary mandrel while the opposite end of said member forms a grip for cooperation with said bracket, whereby relative movement between said bracket and member carries the spinning member towards said seat to press the opposite ends of the rivet towards each other.

6. The combination set forth in claim 3 wherein said last-mentioned means comprises a bracket mounted on the means for rotating the mandrel, and a manually operated member pivotally mounted at a midportion thereof on said bracket; one end of said last-mentioned member carrying an apertured seat fitting against the head of the rivet through which passes the rotary mandrel while the opposite end of said member forms a grip for cooperation with said bracket, whereby relative movement between said bracket and member carries the spinning member towards said seat to press the opposite ends of the rivet towards each other, a spring between the bracket and grip normally separating them preparatory to manual actuation, and an adjustable limit stop cooperating with the relatively movable members to limit the extent of movement therebetween and the consequent pressure against the opposite ends of the rivet.

THEODORE A. REPPER.
